(57) **CLAIM**

The ornamental design for a bag, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of a bag showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of the bag with a long shoulder strap.

The dash-dash broken lines in the drawings depict portions of the bag that form no part of the claimed design.

1 Claim, 9 Drawing Sheets
(9 of 9 Drawing Sheet(s) Filed in Color)
